UNITED STATES PATENT OFFICE.

GEORGE W. GOLDSWORTHY, OF PITTSBURGH, PENNSYLVANIA.

PLATE-PRINTING MACHINE.

Application filed November 26, 1928. Serial No. 150,767.

The present invention relates to plate-printing machines, and more particularly to a device for positioning the sheet of paper upon the plate.

In plate-printing machines, the printing is done by an engraved plate, which is supplied with ink to fill the engraved depressions therein, which ink is later transferred to a sheet of paper pressed against the engraved plate. The plate-printing process is commonly employed for printing engravings, such as bank notes, stock certificates, bonds, etc. The standard plate-printing machines usually comprise beds or slabs one or more that are driven by an endless conveyor and upon which engraved plates are mounted. Each bed travels in a rectangular path beneath an ink font which applies ink to the plate to fill the engraved inscription; then beneath a wiper which removes the surplus ink from the face of the plate, allowing the ink to remain in the depressions; then past an operator who, with his hand, finishes wiping the plate; and then to a second operator who manually lays the dampened sheet of paper upon the plate and sees that it remains in position as the plate moves beneath the impression roller which presses the paper against the plate, so that the ink is transferred from the engraved inscription on the plate to the dampened paper. The printed paper is then removed by a third operator, who inspects it; and the cycle of operations is repeated.

In order to have the ink take properly, the paper must be slightly moistened which not only makes the paper limp and harder to handle, but which may result in uneven expansion of the paper in different sheets. Heretofore, the positioning of the paper on the plate has been universally carried out as a manual operation, requiring considerable skill and care on the part of the operator, as well as careful notching of the paper with notches which the operator can match with marks on the edges of the printing plate. Most engravings, such as bank notes, bonds, stock certificates, etc., are printed on both sides and are often printed in more than one color. In order to get a proper matching of the printing, it has been customary, after the first printing operation on the sheet, to notch the sheets to form notches in their edges which the operator can match with marks on the printing plates, which

subsequently print upon the sheet. This not only requires skill and care on the part of the operator, but requires a considerable amount of manual work in notching the sheets properly before going to the operator who feeds the machine. Then, after printing, each sheet has had to be trimmed singly on two adjacent sides, after which the sheets are stacked and the other two sides trimmed.

I am able to meet the exacting requirements as to accurately positioning the dampened sheet of paper upon the printing plate by means of the feeding and positioning device herein described.

In the drawings, I have illustrated the invention as applied to the standard plate-printing machine, and while its specific embodiment has been designed with particular reference to such machine, it is to be understood that the invention might be applied to other types of plate-printing machines.

In the drawings:

Figure 1 is a plan view of a plate-printing machine having my feeding and positioning attachment applied thereto;

Figure 2 is a side elevation of the machine;

Figure 3 is an enlarged side elevation of the feeding and positioning mechanism;

Figure 4 is a plan view of the feed bed;

Figure 5 is a section along the line V—V of Figure 4;

Figure 6 is a section along the line VI—VI of Figure 4;

Figure 7 is an enlarged section along the line VII—VII of Figure 4;

Figures 8, 9 and 10 are detail elevations showing three positions of the latch which is engaged by a dog on the traveling bed to operate the feed motion;

Figures 11 and 12 are a plan view and an end elevation, respectively, of a modified form of dog;

Figure 13 is a detailed enlarged section along the lines XIII—XIII of Figure 8; and

Figure 14 is a detail perspective view of the finger stop mechanism.

Referring to the illustrated embodiment of the invention, the printing machine comprises a square table 1, having a rectangular track 2, in which travel one or more traveling beds 3, upon which the engraved printing plates 4 are mounted. The traveling beds are moved continuously in the direction indicated by the arrow by means of a conveyor

such as an endless sprocket chain 5, which is provided with upstanding pins 6, which engage in holes in the bottom of the beds 3. One, two or four beds may be employed, depending upon the speed of the machine and the rapidity of the operators. The engraved plate 4 is inked by an ink font 7, which spreads ink uniformly over the face of the engraved plate. The inked plate then passes beneath a wiper 8, which consists of two rolls 9 and 10, the wiping cloth being unwound from one roller to the other, so as to present a clean wiping surface to the plate. The plate as it leaves the wiper is then manually wiped by the hand of an operator who stands at the station A. The operator brushes his hands with chalk and then passes them over the plate to remove any vestiges of ink on the surface of the plate between the inscriptions, so that the engraving will not be smeared. The machine so far described is a standard plate-printing machine. The details of the bed motion are set forth in the Read Patent, No. 635,978 of October 31, 1899, and need not be described further.

In the standard machines as now used, the printing plate as it leaves the operator at station A passes to an operator who stands at the station B. This operator takes a dampened sheet of paper from a stack and with the help of the operator A carefully positions the sheet of paper upon the plate 4, as it passes to the impression roller 11, which is a resilient cloth-covered roller which presses down upon the paper, so that the ink is transferred from the engraved plate to the dampened paper. Antifriction rolls 12 are usually employed to support the bed 3 and the plate 4, carried thereby, as they pass beneath the impression roller 11.

As before stated, the operator A, assisted by the operator B, must carefully position the sheet of paper upon a printing plate, this being done in accordance with present practice by the aid of notches cut in each edge of the sheet which the operators match with lines scratched upon the edge of the printing plate. After the plate passes beneath the impression roller 11, the sheet of paper or engraving is lifted from the plate by an operator at the station marked C, who also inspects the work.

The present invention relates particularly to a device for feeding the sheet of paper and accurately positioning it upon the printing plate 4, as it passes to the impression roller 11. My positioning device does away with the necessity for notching the edges of the paper, as well as eliminating the trimming of the sheets singly after printing, thus effecting a great practical economy in plate-printing establishments. It also simplifies the work of the operators at A and B and frees the operation of mistakes made by these operators in matching the notches in

the paper with the scratches on the edges of the plates.

The single sheets of dampened paper are preferably supplied to the positioning device by the operator at station B, but the work of this operator is greatly simplified and accurate positioning is assured, because all this operator has to do is to place the sheet against outside gauges or stops upon the feed bed, from which the paper is automatically fed to and positioned upon the printing plate.

Referring to the drawings, the feeding and positioning attachment comprises a feed bed 13, upon which the operator at the station B manually places a sheet of dampened paper. The feed bed is provided with an adjustable side gauge 14, against which the operator fits one edge of the sheet. This gauge 14 is made adjustable by means of the clamping nut 15, and is preferably of the form shown, consisting of an inclined plate beneath which the edge of the paper is fitted. The front gauge against which the operator positions the front edge of the sheet is formed by stop fingers 16, which project down in front of the plate when it occupies its normal position to receive the sheet of paper.

After the operator has positioned a sheet of paper against the gauges 14 and 16, the feeding mechanism is operated in synchronism with the movement of the printing plate 4 to grip the paper and feed it to and accurately position it upon the printing plate 4. For this purpose, the feed bed 13, which consists of a flat metal plate, is mounted by sliding bearings 17 upon supporting rods 18. Springs 19 hold the feed bed 13 in its normal position, but allow it to be moved to the right, as viewed in Figures 2, 3 and 4, to feed the paper to the traveling printing plate. The return movement of the feed bed 13 under the influence of the springs 19 is cushioned by the dash pot 19^a, formed by a cylinder 19^b in the supporting frame, and a cooperating plunger 19^c on the movable feed bed 13.

The operating movement of the feed bed is imparted to it by means of an adjustable dog 20, carried upon one side of each traveling bed 3, upon which the printing plate 4 is bedded. A dog 20 is adjustably mounted on each bed by means of screws 21, engaged through slots 22 in the dog. Each dog 22 has a riser or ramp 23, a horizontal portion 24 and an upstanding catch or dog proper 25.

In Figures 11 and 12 is shown a modification in which an adjusting screw 26 is provided for more delicately adjusting the position of the dog 20 on the bed 3.

As each bed 3 reaches the corner of the machine at the operating station B and makes its turn and travels toward the impression roller 11, the associated dog 20

engages a latch 27, which is carried on the feed bed 13. The latch 27 comprises a slotted plate 28, which has two studs 29 and 30, which project through a slot 31 in a plate 32 which is carried by and projects downwardly from the feed bed 13. The studs 29 and 30 carry the antifriction rollers 33 and 34, respectively. The plate 28 has adjustably mounted in its slot an L-shaped foot 35, upon the toe of which is carried an antifriction roller 36. A leaf spring 37 tends to hold the latch 27 in the position shown in Figure 8, which is its normal position when not engaged by the dog 20 and the position which it has when the operator places the sheet of paper upon the feed bed 13.

The operator usually has the sheet of paper positioned against its gauges on the feed bed 13 by the time the printing plate is making the right-angled turn at the operator's station. As the printing plate and its supporting bed 3 move toward the impression roller 11, the inclined or ramp surface 23 of the dog 20 passes beneath the latch 27 and raises the roller 36, turning the latch from the position shown in Figure 8 to that shown in Figure 9. This movement operates the gripping fingers 38 which engage the upper edge of the paper. The gripping fingers 38 normally lie below the surface of the feed bed 13, as indicated in Figure 5, but when the dog 20 rides under the latch 27, the spring-gripping fingers 38 are thrown over to engage the upper edge of the paper. This motion is imparted by a lever 39, which is pivoted at 40 beneath the feed bed. The downwardly projecting end 41 of this lever lies in the path of the upper end of the latch plate 28 as its upper end is swung to the right from the position shown in Figure 8 to that shown in Figure 9. The other end of the lever 39 fits into a rack bar 42, which is slidably mounted beneath the feed bed 13 by means of the taper headed studs 43 which engage in a taper slot 44 in the rack bar 42. The movement of the rack bar 42 is transmitted through a pinion 45 to a shaft 46 upon which the spring-gripping fingers 38 are mounted. The shaft 46 is journaled in a frame 47, which is adjustably mounted on the bottom of the feed bed and may be moved back and forth and clamped in position by the wing nut 48, to position the spring fingers 38 for sheets of paper of different lengths. As soon as the spring-gripping fingers 38 engage the paper, the paper is positively handled thereafter, and the operator is relieved of any further care. All the operator has to do is to position the paper against the side and end gauges 14 and 16 in position to be gripped by the spring fingers 38. The position of the fingers 38 may be adjusted for different sized sheets by lowering the pinion 45 and

re-engaging it as desired with the rack 42. The fingers are made of spring metal so as to give a yielding grip.

After the paper has been fed into position to be engaged by the impression roller 11, the spring fingers are released by the restoring movement imparted to the lever 39 by means of the spring 49, which tends to return the lever 39 to its original position, as indicated in Figure 8. After the gripping fingers 38 have engaged the paper and just before the feed bed 13 starts to move, the end gauges 16 are lifted out of the way by means of a downwardly projecting lever 50 on the shaft 51, which carries the gauge fingers 16 and which is raised and held by the bar 50^a, carried on the left-hand edge of the traveling bed 3 as it passes with its plate to and under the roller 11. The gauge fingers 16 are restored to normal position after the bed has passed beyond them by means of the weighted arms 52 on the end of the shaft 51.

When the gauge fingers 16 are being lifted, the horizontal portion 24 of the dog 20 is passing beneath the latch 27, and immediately thereafter the projection 25 catches the heel of the L-shaped latch piece 35. When the catch 25 first engages the heel of the latch piece, the pins 29 and 30 are in the position shown in Figure 9, in which the latch piece is not free to turn. The dog, therefore, by engagement of the latch piece carries it along with it and thereby moves the feed bed 13 along its sliding supporting rods 18 against the pressure of its restoring springs 19. The feed bed has a sufficient forward movement to feed the projecting edge of the paper between the printing plate 14 and the impression roller 11. The feeding movement imparted to the feed bed 13 is usually about four or five inches. After the forward edge of the paper has been sufficiently engaged by the impression roller 11, the feed bed is released and moves back to its initial position. This is accomplished as follows:

As the dog 20 carries the latch 27 to the right, as viewed in Figures 9 and 10, the feed bed 13 is descending along its inclined side bars 18, so that the supporting plate 32 is moving downward relatively to the latch 27. This movement continues until the stud 29 comes opposite the enlargement 53 in one side of the slot 31. The pin 29 then moves into this enlargement, and the latch is permitted to be tilted into the position shown in Figure 10, whereupon its heel is released by the dog projection 25. The feed bed 13 is then free to be moved by its restoring springs 19 upwardly along the inclined rods 18 to its initial position. The latch 27 is restored to its original position, as shown in Figure 8, by means of the leaf spring 37, and the gripping fingers 38 are

thrown back beneath the plate and the feed bed is then in position to have another sheet of paper placed upon it by the operator as soon as the bed 3, with its plate 4, has passed beneath the impression roller 13 and allowed the end gauge fingers 16 to descend into their gauge position.

One side and the forward edge of the sheet of paper are accurately positioned by the operator against the gauges 14 and 16, so that the lower edge and one side edge of the sheet of paper are given a fixed position with relation to the printing plate as the sheet of paper is applied thereto. The paper is gauged from its forward edge before the gripping fingers 38 engage the paper, so that any inequality or swelling of the paper, due to its dampening, does not throw the paper out of registry with the printing plate.

In order to permit the accurate gauging of the forward edge of the paper by the fingers 16, a fixed apron 54 is provided having slots or depressions 55 in which the gauge fingers 16 are engaged. When the feed bed 13 is moved forwardly, it moves over the apron 54, the extreme forward edge of the paper which projects beyond the lowermost edge of the feed bed and on to the apron 54, moving over the apron 54 and into the bite between the impression roller and the plate.

The feed bed motion is preferably imparted to it, as shown, by the travel of each printing plate and its supporting bed, so that there is always an absolute synchronism between the travel of the printing plate to the impression roller and the movement of the feeding and positioning mechanism, thus insuring an accurate positioning of the paper on the printing plate.

The parts of the machine have the various accurate adjustments illustrated, so that the position of the paper on the feed bed and the movement of the feed bed relative to the printing plate can be nicely adjusted so that the sheet of paper would be positioned accurately upon the printing plate. That is, of course, very important in high grade work, such as two-color engraving printing.

While I have illustrated and described the preferred embodiment of my invention, it is to be understood that the invention is not limited to its illustrated embodiment, but may be otherwise embodied within the scope of the following claims.

I claim:

1. The combination with a plate-printing machine having a horizontally movable printing plate and an impression roller for pressing the paper on the plate to receive the ink therefrom, of means for pushing the paper onto the plate.

2. The combination with a plate-printing machine having a traveling printing plate movable along a single plane and a cooper-

ating roller for pressing the paper on the plate to receive the ink therefrom, of means operating in synchronism with the movement of the plate for pushing a sheet of paper onto the plate as it passes to the roller. 70

3. The combination with a plate-printing machine having a traveling printing plate and a cooperating roller for pressing a sheet of paper on the plate to receive the ink therefrom, of means operated by the travel 75 of the plate for projecting a sheet of paper to the plate and positioning it thereon as it passes to the roller.

4. The combination with a plate-printing machine having a horizontally traveling printing plate and an impression roller beneath which the plate travels for pressing a sheet of paper against the plate to receive ink therefrom, of an inclined feed bed adapted to receive a sheet of paper and moved in synchronism with the travel of the plate for feeding the paper forwardly and downwardly to the plate and positioning it thereon as the plate passes to the impression roller. 80

5. The combination with a plate-printing machine having a traveling printing plate and an impression roller for pressing the paper on the plate to receive ink therefrom, of a feed bed beneath which the plate travels 95 to the roller and a dog moved with the travel of the plate for engaging the feed bed and operating it to feed a sheet of paper to the plate and position it thereon.

6. The combination with a plate-printing 100 machine having a traveling printing plate and cooperating means for pressing a sheet of paper upon the plate to receive ink therefrom, of a feed bed positioned above the printing plate as it travels to the pressing 105 means, said feed bed having gauges against which a sheet of paper may be positioned and having means for gripping the paper after it is positioned on the feed bed and transferring it to the plate and positioning 110 it thereon.

7. The combination with a plate-printing machine beneath a traveling printing plate and a cooperating roller beneath which the plate travels for pressing a sheet of paper 115 against the plate to receive ink therefrom, of a reciprocating feed bed positioned above the plate as it travels to the roller, gauges for positioning a sheet of paper upon the feed bed, means for gripping the paper after it is positioned on the feed bed, and means for moving the feed bed toward the roller with the speed of travel of the printing plate for feeding a sheet of paper to 120 the plate as it passes to the roller.

8. In a plate printing machine, the combination with an endless conveyor, a printing plate carried thereby, and an impression roll cooperating with the plate for pressing a sheet of paper thereagainst, of a feed bed 125

actuated by the movement of the plate for feeding and positioning a sheet of paper on the plate.

9. In a plate printing machine, the combination with a conveyor, a plurality of printing plates carried thereby, and an impression roller successively cooperating with the plates during the travel of the conveyor for pressing sheets of paper thereagainst, of a feed bed actuated in accordance with the movement of the plates for feeding and positioning sheets of paper to the plates in substantially the same relative positions.

10. In a plate printing machine, the combination with a conveyor, a plurality of printing plates carried thereby, and an impression roller successively cooperating with the plates during the travel of the conveyor for pressing sheets of paper thereagainst, of a feed bed actuated in accordance with the movement of the plate for feeding and positioning sheets of paper to the plate in substantially absolute registry.

11. In a printing machine, the combination with a movable printing plate and a movable feed bed actuated by the movement of the plate for feeding paper thereto, of gripping fingers carried by the feed bed and movable independently thereof in accordance with the position of the plate.

12. In a printing machine, the combination with a movable printing plate and a movable feed bed actuated by the movement of the plate for feeding paper thereto, of gripping fingers carried by the feed bed and

actuated substantially simultaneously with the feed bed in accordance with the position of the plate.

13. In a printing machine, a movable printing plate, a roller cooperating with the plate, and a feed bed for positioning sheets of paper into engagement with the roller and the plate in accordance with the movement of the plate, the feed bed comprising gripping fingers movable relatively thereto and separately actuated by the plate.

14. In a feed bed for a printing machine, a movable base, gripping fingers extending through the base and movable independently thereof, means for adjusting the normal position of the fingers relative to the base, and means for moving the fingers in the base in a predetermined sequence in accordance with the movement of a printing plate.

15. In a movable feed bed for a printing machine, a base, adjustable gripping fingers extending therethrough, and means for simultaneously controlling the independent movement of the base and fingers.

16. The combination with a plate printing machine having a traveling printing plate and an impression roller for pressing the paper thereagainst, of a feed bed beneath which the plate travels to the roller, and means for moving the feed bed in the direction of travel of paper being fed to the plate and positioned thereon.

In testimony whereof I have hereunto set my hand.

GEO. W. GOLDSWORTHY.

CERTIFICATE OF CORRECTION.

Patent No. 1,649,583.

Granted November 15, 1927, to

GEORGE W. GOLDSWORTHY.

It is hereby certified that error appears in the printed specification of the above numbered patent requiring correction as follows: Page 1, line 14, strike out the words "one or more" and insert the same to follow after the word "comprise" in the same line; and that the said Letters Patent should be read with this correction therein that the same may conform to the record of the case in the Patent Office.
